UNITED STATES PATENT OFFICE.

AXEL R. GUSTAFSON, OF CHICAGO, ILLINOIS.

IRONING-MACHINE.

1,288,566.

Specification of Letters Patent. Patented Dec. 24, 1918.

Application filed October 23, 1917. Serial No. 198,050.

To all whom it may concern:

Be it known that I, AXEL R. GUSTAFSON, a citizen of the United States, residing at Chicago, in the county of Cook and State of Illinois, have invented certain new and useful Improvements in Ironing-Machines, of which the following is a specification.

This invention relates to improvements in ironing machines and one of its objects is to provide a machine of the hand or power type which is simple in construction and efficient in operation. A further object is to provide an ironing machine that will thoroughly dry such garments as may be damp, during the ironing operation, without danger of scorching or burning the garments. A further object is to provide a machine of this type that can be used with the minimum of danger of bodily injury to the operator.

20 A further object is to provide an ironing machine having a plurality of heated rolls arranged in the arc of a circle upon a stationary frame, said rolls being heated independently of each other so that any desired temperature may prevail in any given roll; said heated rolls, further, being adapted for simultaneous engagement with and disengagement from a padded roll journaled in movable bearings, said padded roll and bearings being under manual control of the operator.

With the foregoing and other objects in view the invention consists in the combination and arrangement of parts to be herein-after fully described, pointed out in the appended claims and illustrated in the accompanying drawings which form a part of this specification and in which—

40 Figure 1 is a view of my improved ironing machine in end elevation, gas being used as a heating element.

Fig. 2 is a front view of the machine.

Fig. 3 is an end elevation opposite to that shown in Fig. 1.

45 Fig. 4 is a fragmentary end elevation illustrating a slight change made in the machine showing the padded roll driven by a belt.

Fig. 5 is a top plan view of Fig. 4.

50 Fig. 6 is a fragmentary view of the machine illustrating the means employed to impart motion to the padded roll to cause it to move into and out of engagement with the heated rolls.

55 Fig. 7 is a section on line 7—7 of Fig. 6.

Like reference characters denote corresponding parts throughout the several views.

My ironing machine comprises the frame 1 provided with feet 2 and formed with the angular extension or neck-frame 3, the sides 60 of the neck-frame being connected by the stay rod 3^a. The frame is formed with the end ledges 4, one of which carries the motor 5, and with the transverse stay rods 6 to which the receiving table 7 is suitably bolted. In the neck frame the heated roll shafts 8, 9, 10 are journaled, said shafts being equidistant from each other and arranged in the arc of a circle. Gas for heating purposes is admitted to the rolls 11, 12, 70 13 of shafts 8, 9, 10 through the medium of said shafts which are of hollow formation and in communication with the branch pipes 14, 15, 16 which are fed through the nipple 17 adapted to receive one end of a flexible 75 gas transmission hose (not shown). Each branch pipe 14, 15, 16 is provided with a valve 18 whereby the amount of gas fed to any one roll is controlled and the temperature of the several rolls always regulated. 80 The roll shafts 8, 9, 10 are provided upon one end with the gears 19, 20, 21 which are never in mesh with each other due to the distance between the said roll shafts. The gear 21, however, is always in mesh with a 85 relatively small gear 22 fast upon the stub shaft 23 that is journaled in one side of the frame 1 and that carries the large drive wheel 24 that is connected by a belt (not shown) to the motor pulley 25.

90

A padded roll 26 is fast upon a shaft 27 journaled in blocks 28 slidably arranged in the slotted portions of the movable bearings 29 upon the tension springs 30 seated upon plates 31 also arranged in the slotted portions of said bearings and adjusting screws 32 carried by said bearings engage with said plates 31 to adjust the same relatively to said blocks 28 when desired. Brace arms 33 made fast to the bearings 29 support a feed 100 table 34 disposed in advance of the padded roll 26.

Guide arms 35 connected by pivots 36 to the ends of the frame 1 are also pivotally connected to the bearings 29 to partially 105 support and guide the same and links 37 also pivotally connected to said bearings 29 depend from said bearings and are formed with the obliquely enlarged portions 38 wherein the obliquely disposed elongated slots 39 are 110

formed, said slots 39 receiving the relatively small lugs 40 which are integral with the frame 1, said lugs being disposed at substantially a 45° angle with the frame and 5 serving as guides for the said links 37. Guide plates 41 secured by bolts or screws 42 to the lugs 40 serve to retain the said links in operative relation. The links 37 at their lower ends are connected by pitmen 43 10 with the racks 44 which are fast upon a connecting rod 45 fulcrumed upon a post 46 and provided with a pedal 47. Dogs 48 pivotally connected to the frame 1 are normally in engagement with the toothed portions 15 of the racks 44 to retain them in horizontal position, as shown in Fig. 1, said dogs being also engaged by pitmen 49 connected to links 50 adjustably secured to a transverse rod 51 journaled in the sides of 20 the frame 1, said rod 51 being provided with an operating handle 52.

The shaft 27 of the padded roll 26 is provided at one end with the large gear 53 which, in one position of said roll with respect to the heated rolls, is adapted for engagement with the aforesaid gears 19, 20, 21, 25 said shaft 27 and padded roll 26, at that time, receiving power from the gear 21 and transmitting the same to the gears 19, 20. 30 When the dogs 48 are in engagement with the outermost teeth of the racks 44 the shaft 27 of the padded roll is disengaged from the heated rolls and, further, it is substantially at the center of a circle in an arc of whose 35 circumference the shafts 8, 9, 10 of the heated rolls lie. The longitudinal center line of the slot 39 of link 37 lies parallel with the radius of the said circle that would connect shafts 27 and 9, the movement of the 40 padded roll from engaged to disengaged relation with the heated rolls and vice versa is little, and so it follows that said heated rolls being arranged close together, the padded roll when engaging one of the gears 45 19, 20, 21 will engage them all, and simultaneously. I preferably heat the roll 11 to a greater degree than either of the other rolls, and the roll 13 least of all. A garment to be ironed is fed between the padded 50 roll and roll 11 by hand and it passes over the padded roll and beneath the three heated rolls and then drops upon the receiving table 7 from which it may be removed. A damp garment will be thoroughly dried by the 55 rolls 11 and 12 and ironed and finished off by the roll 13. The decreasing heat encountered by the garment as it passes along will greatly lessen the tendency to scorch or burn the same although ironing it 60 thoroughly. In Fig. 1 the machine is shown inoperative because the padded roll and heated rolls are disengaged. The motor 5 drives the wheel 24 which, through the medium of gear 22, drives the gear 21 con- 65 stantly. To start the machine the operator

depresses the pedal 47 until the padded roll engages with the heated rolls and he then, by means of handle 52 moves the dogs 48 into engagement with the rack 44 as shown in Fig. 3 when the parts are retained in adjusted position. By raising the handle 52 again the padded roll, through gravity, will move away from the heated rolls. 70

In Figs. 4 and 5 a modified form of machine is shown. Pulleys 54 are journaled in 75 sliding bearings 55 upon the table 34 and a feed canvas 56 driven by said pulleys passes about the padded roll and feeds the garments between the same and the heated rolls. The bearings 55 are arranged upon 80 adjusting screws 57 controlled by hand wheels 58 to take up slack in the feed belt. 85

What is claimed is:

1. In an ironing machine, a frame, heated rolls supported thereby, a padded roll adjustably supported by said frame, and means operatively engaging said padded roll for causing the same to engage said heated rolls simultaneously and to become disengaged from said heated rolls, said means including 90 obliquely slotted links, the slotted portions thereof being connected to said frame whereby said padded roll is guided.

2. In an ironing machine, a frame, heated rolls supported thereby, a padded roll adjustably supported by said frame, and manually operable means engaging said padded roll for causing the same to engage said heated rolls simultaneously, said means including obliquely slotted links and connections between the slotted portions of said links and said frame whereby said padded roll is guided. 95

3. In an ironing machine, a main frame, a neck-frame carried thereby, rotary heated rolls journaled in said neck-frame, a padded roll adjustably carried by said main frame, and means connecting said padded roll and main frame for moving said padded roll into simultaneous engagement with said heated rolls, said means including obliquely slotted links having connections between the slotted portions of said links and main frame whereby said padded roll is guided relatively to said neck frame. 105

4. In an ironing machine, a main frame, a neck-frame carried thereby, heated rolls arranged in the arc of a circle and journaled in said neck-frame, a padded roll adjustably carried by said main frame, and means for effecting simultaneous engagement of said padded roll with said heated rolls, said means including obliquely slotted links. 110

5. In an ironing machine, a main frame, a neck-frame carried thereby, three heated rolls arranged in the arc of a circle and journaled in said neck-frame, the center roll being equidistant from the other two rolls, a padded roll adjustably carried by said main frame, means for effecting simultaneous en- 115

gagement of said padded roll with said heated rolls, said means including obliquely slotted links and means for driving the several rolls when in engaged relation.

- 5 6. In an ironing machine, a frame, heated rolls carried by said frame and arranged in the arc of a circle, a padded roll, means associated with said frame for adjustably supporting said padded roll, said means including obliquely slotted links in the slots of which frame lugs are disposed, said links serving to guide said roll-supporting means, and means for actuating the aforesaid means whereby said padded roll may be moved into engagement with said heated rolls simultaneously.

7. In an ironing machine, a main frame, a neck-frame carried thereby, heated rolls carried by said neck-frame and arranged in the arc of a circle, a padded roll, means associated with said main frame for adjustably supporting said padded roll, said means including obliquely slotted links in the slots of which frame lugs are disposed, said links serving to guide said roll-supporting means, the longitudinal center lines of said oblique slots being disposed parallel with a radius connecting the shaft of said padded roll with the shaft of one of said heated rolls, and means for actuating said padded roll-supporting means whereby said padded roll may be moved into simultaneous engagement with said heated rolls.

- 30 8. In an ironing machine, a frame, heated rolls carried by said frame and arranged in

the arc of a circle, a padded roll, means associated with said frame for adjustably supporting said padded roll, said means including obliquely slotted links in the slots of which frame lugs are disposed, said links 40 serving to guide said roll-supporting means, cover plates bolted to said frame lugs and engaging said slotted links, actuating means for said padded roll whereby the same may be moved into simultaneous engagement 45 with said heated rolls, and means for releasably locking said padded roll in adjusted position with relation to said heated rolls.

9. In an ironing machine, a frame, heated 50 rolls carried by said frame and arranged in the arc of a circle, a padded roll, guide arms pivotally connecting said padded roll and said frame, obliquely slotted links connected to said padded roll, lugs formed on said 55 frame and disposed in the slotted portions of said links, cover plates for said slotted links bolted to said lugs, fulcrumed racks, connections between said fulcrumed racks and slotted links, and means for moving said 60 racks upon their fulcrums.

In testimony that I claim the foregoing as my own I have hereto affixed my signature in the presence of two subscribing witnesses.

AXEL R. GUSTAFSON.
